UNITED STATES PATENT OFFICE.

STEPHEN E. BURKE, OF HAMILTON, INDIANA, ASSIGNOR OF ONE-HALF TO JONAS ALLAMONG, OF HAMILTON, INDIANA.

DRAFT-REGULATOR.

1,131,036.

Specification of Letters Patent.

Patented Mar. 9, 1915.

Application filed June 9, 1914. Serial No. 844,069.

To all whom it may concern:

Be it known that I, STEPHEN E. BURKE, a citizen of the United States, residing at Hamilton, in the county of Steuben and State of Indiana, have invented a new and useful Draft-Regulator, of which the following is a specification.

The present invention appertains to a draft regulator for the boilers of locomotive, traction, and similar engines, and aims to provide novel and improved means for automatically checking or retarding the draft through the flues, when the door of the fire box is opened, and to thereby avoid the contraction of the flues and crown sheet incident to the sudden influx of cold air as is the case in ordinary engines.

The present invention contemplates the provision of an air inlet pipe carried by the boiler shell and coöperating with the exhaust or discharge pipe for the steam which projects toward the smoke stack, as usual, for ordinarily creating a forced draft, in combination with unique means for opening the passage through the said air pipe when the coal door of the fire box is opened, and for ordinarily closing the passage through the said air pipe when the said door is closed.

Another object of the present invention is to so arrange the air inlet pipe, that it will coöperate with the steam exhaust pipe, in a thoroughly efficient manner for the intended purposes.

It is also within the scope of the present invention, to provide an appliance of the nature indicated, which will be comparatively simple, and inexpensive in construction, which may be readily applied to existing or ordinary boilers as well as new ones, and which will be convenient, practical and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The present invention has been illustrated in its preferred embodiment, in the accompanying drawing, wherein—

Figure 1 is a side elevation of a locomotive or traction boiler having the invention applied thereto. Fig. 2 is an enlarged rear view thereof. Fig. 3 is an enlarged sectional view taken on the line 3—3 of Fig. 1. Fig. 4 is a sectional view taken on the line 4—4 of Fig. 3.

In the drawings, there is illustrated an ordinary locomotive or traction engine boiler, including the shell 1, having the fire box 2 at its rear end, and the fire box having the rear coal door 3. The boiler shell 1 is provided with the smoke stack 4 at its forward end, as usual, and the flues 5 establish communication between the fire box 2 and the discharge chamber or compartment 5^a within the forward end of the boiler shell 1 and communicating with the smoke stack 4. The steam exhaust pipe 6 projects upwardly within the chamber or compartment 5^a toward the smoke stack 4, in order that the steam in being exhausted, will create a forced draft through the flues 5, as usual. The foregoing structure is a typical one, it being understood, at the outset, that the present invention is applicable to various locomotive, traction and portable boilers, with equal propriety and success, as will be obvious to those skilled in the art.

In carrying out the present invention, an air inlet pipe 7 is disposed within the chamber 5^a, the pipe 7 being preferably curved or arcuate, and having one end attached interiorly to one side of the shell 1, while the other end of the pipe 7 projects upwardly in advance of and directly adjacent the nozzle end of the exhaust pipe 6, or at that side of the exhaust pipe 6 remote from the flues 5. The upper end of the pipe 7, which projects above the upper or nozzle end of the exhaust pipe 6, is cut obliquely or diagonally, as at 8, so as to lie directly to one side of the current or stream of steam passing from the exhaust pipe 6 to the stack 4.

As a means for controlling the flow of air through the air pipe 7, a longitudinal shaft 9 is disposed along one side of the boiler, and its forward end portion is journaled through a pair of bearings 10 secured to the

side of the shell 1 directly in rear and in advance of the outer end of the pipe 7. A valve 11 is secured to the forward end portion of the shaft 9 between the bearings 10, 5 and is adapted to swing snugly against the side of the shell 1, over the mouth or inlet end 12 of the pipe 7 which communicates through the side of the shell 1 with the atmosphere when the valve 11 is opened. 10 Thus, when the shaft 9 is rocked, the valve or shutter 11 may be swung to and from the end of the pipe 7, to close and open the same, or to control the inlet of air thereto. The rear end portion of the shaft 9 is 15 journaled through bearings 13 attached to the corresponding side of the fire box 2, and when the shaft 9 cannot be straight, the same is rendered flexible by universal joints 9^a, as will be obvious. 20 As a means for automatically actuating the shaft 9, to close and open the valve 11, when the coal door 3 is closed and opened, respectively, the rear end of the shaft 9 is 25 operatively connected to the door 3, as will presently appear. A plate or disk 14 is secured rigidly upon the rear end portion of the shaft 9, and a lever 15 is journaled or fulcrumed intermediate its ends upon the rear end of the said shaft adjacent the plate 30 or disk 14. A link 16 connects the lower end or arm of the lever 15 and the coal door 3, whereby the lever 15 will be oscillated when the door 3 is opened and closed. The upper end or arm of the lever 15 is adapted to 35 engage the stationary lug or pin 17 secured to the plate or disk 14, whereby when the door 3 is closed, to swing the lower arm of the lever 15 therewith, the upper arm of the said lever in engaging the lug 17 will swing 40 the plate or disk 14 to thereby correspondingly swing the shaft 9 to bring the valve or shutter 11 to closed position. In this manner, when the door 3 is closed, the valve or shutter 11 will be closed, to shut off the 45 inlet of air into the pipe 7, and consequently, the forced draft will be established through the flues 5, under ordinary conditions. The plate or disk 14 is also provided with an arcuate series of apertures 18, co- 50 operating with the lower arm of the lever 15, and through which is adjustably insertible, a cotter pin 19. This pin 19 may be adjusted, as seen in Fig. 2, to hold the upper arm of the lever 15 permanently against the 55 lug or stud 17, whereby the plate or disk 14 will be constrained to swing with the lever 15, and consequently, the valve 11 in this event, will swing open and close with the door 3. The pin 19, however, may be 60 adjusted along the apertures 18, to permit a limited oscillatory movement of the lever 15 with respect to the plate or disk 14, whereby the plate or disk 14 will not be swung when the door 3 is opened, until the 65 door has opened a predetermined amount.

It is also possible to entirely remove the pin 19, or to adjust it at such a point remote from the lever 15, as to prevent the plate or disk 14 from being oscillated when the coal door 3 is opened.

In operation, when the device has been properly installed, and assuming the pin 19 to have been set as seen in Fig. 2, then when the coal door 3 is opened, which with the continued forced draft, would cause a sudden influx of cold air into the flues 5, will rock the shaft 9 to open the valve 11. Then, the steam being discharged from the exhaust pipe or nozzle 6, past the end 8 of the air pipe 7 will cause the air to be drawn 80 through the pipe 7 from the atmosphere, to reduce or check the draft through the flues 5, and consequently, the forced draft will be retarded and this will reduce to a minimum, the inflow of cold air into the flues, which 85 would be liable to contract the same. The present device therefore avoids the contraction of the flues, when the coal door 3 is open, and as not infrequently results in leakage, and furthermore, the consumption 90 of fuel is economized, due to the checking of the draft when the coal door is opened. When the coal door 3 is again closed, the shaft 9 being oscillated back to initial position, will again close the valve or shutter 95 11 to close the passage through the pipe 7, and as a result, the forced draft will be resumed.

It is evident from the foregoing, taken in communication with the drawing, that when the door 3 is opened, the lower arm of the lever 15 will be swung outwardly, to engage the pin 19, so as to swing the plate or disk 14 with the lever, the plate 14 being secured upon the shaft 9 will swing the shaft therewith to open the valve 11. Conversely, when the door 3 is swung to closed position, the link 16 will pull the lower arm of the lever 15 inwardly, and the upper arm of the said lever being engaged with the stud or 110 lug 17 will bring the plate or disk 14 back to normal position, to close the valve 11. When the pin 19 is adjusted to permit a limited movement of the lever 15 with respect to the plate 14, the upper arm of the 115 lever 15 will still engage the lug 17, when the door 3 is closed, but the door 3 must first be opened to a predetermined amount before the valve 11 is opened. In this manner, the amount to which the valve 11 is opened, may 120 be regulated by adjusting the pin 19, and when the pin 19 is entirely removed or adjusted considerably remote from the lower arm of the lever 15, the lever 15 may oscillate back and forth when the door 3 is 125 opened and closed, without moving the plate 14 or its shaft 9. This is of advantage for the reason that when the engine is fired to raise steam, it is desirable that the forced draft be continued, even while the door 3 130

is opened. As soon as the steam pressure rises sufficiently, the pin 19 may be adjusted, so as to cause the plate 14 to be oscillated when the door 3 is opened and closed, for 5 the purpose of opening and closing the valve 11 as above described.

An important and salient feature of the present invention, resides in the arrangement of the air pipe 7 within the chamber 10 5^a, whereby when the passage through the pipe 7 is opened, the reaction caused by the suction of air through the pipe 7 when the steam is exhausted, will tend to counteract the draft through the flues 5, or will create 15 a back pressure which will reduce the draft to a minimum. The nozzle end of the pipe 7 is disposed in advance of the nozzle end of the exhaust pipe 6, to provide the said function, and furthermore, there will be no interference with the vacuum created by the 20 exhausting steam, under ordinary conditions, when the passage through the air pipe is closed.

The present device is a comparatively simple 25 and inexpensive one, and may be readily installed upon various locomotives and traction engines, to operate successfully for the purposes intended, and furthermore, the device is of such construction as to operate 30 under various atmospheric conditions without the liability of the impairment of the device due to exposure.

It has been found that with ordinary 35 boilers, when the coal door is opened, the steam pressure will fall off from five to ten pounds, which results in a waste of fuel, but with the present device, this waste of fuel will be reduced to a minimum, or entirely eliminated.

Having thus described the invention, what 40 is claimed as new is:

1. The combination with a boiler including a shell having a discharge chamber, flues leading to the said chamber, a stack communicating with the said chamber, and an exhaust pipe projecting within the said chamber and having its nozzle end projecting toward the said stack, of an air inlet pipe communicating with the atmosphere and projecting into the said chamber, the discharge 45 end of the air pipe projecting above and directly adjacent the nozzle end of the exhaust pipe, being cut obliquely, and being disposed at that side of the exhaust pipe remote from the flues, and means for controlling the inlet of air into the air pipe. 55

2. The combination with a boiler including a fire box door, and an exhaust pipe for creating a forced draft, of an air inlet pipe coöperating with the said exhaust pipe, a 60 shaft, a valve adapted to be actuated by the shaft for controlling the inlet of air into the said pipe, a lever mounted loosely upon the said shaft, a link connecting the lever and door, a plate secured rigidly upon the 65 shaft adjacent the said lever, and a pair of pins carried by the said plate and adapted to be engaged by the said lever when it is swung, one of the said pins being adjustable to regulate the amount to which the 70 valve is opened when the door is opened.

In testimony that I claim the foregoing as my own, I have hereto affixed my signature in the presence of two witnesses.

STEPHEN E. BURKE.
